MACHINE FOR MAKING SANITARY NAPKINS

Charles A. Fourness, Appleton, and Charles J. Greiner, Menasha, Wis., assignors to International Cellucotton Products Company, Chicago, Ill., a corporation of Delaware

Application August 14, 1936, Serial No. 96,026

6 Claims. (Cl. 154—29)

This invention relates to machines for making sanitary napkins, and has reference more particularly to accessory means for applying to one or both sides of the creped paper wadding which forms the body of the napkin, a cover sheet of smooth soft absorbent paper or the like to render the napkin more comfortable when worn.

Typical examples of a sanitary napkin machine of a kind to which our present improvements are adapted are shown in Letters Patent to Oscar T. Thompson, No. 1,869,177, granted July 26, 1932 and in Letters Patent to Charles A. Fourness and Oscar E. Hagen, No. 2,036,209, granted April 7, 1936. In these machines a continuous flat sheet or strip of creped paper wadding is fed by a reciprocating clamp or gripper into the field of action of a die mechanism comprising a lower stationary die and an upper vertically reciprocating die, both dies carrying knives which cooperate to cut the individual articles from the sheet or strip, and the upper die also carrying a pair of embossing dies by which the trade name of the article is embossed on the upper surface of the two ends of the article. The relation of the severing knives and the embossing dies is such that, as the foremost article is cut off the next or the second succeeding article is embossed, as disclosed in Patent No. 2,036,209, above referred to.

For the purpose of applying the covering sheets to the two sides of the wadding sheets, we journal on the machine frame, above and beneath the horizontal bed on which the feed mechanism reciprocates, a pair of spools carrying rolls of the covering sheets and provide suitable guides for directing the free ends of the sheets into the wadding clamp or gripper and into contact with the upper and lower sides respectively of the wadding sheet, so that, as the wadding is advanced the two covering sheets are advanced with it. Light brakes are applied to the two cover sheet rolls to maintain a light tension on the cover sheets as they are drawn forward.

We have found in practice that the impression of the top cover sheet into the wadding sheet by the embossing dies created a sufficient grip of the cover sheet on the wadding to prevent relative slip between the two sheets during a forward feed movement, but we also found that in the case of the bottom cover sheet, since it was not impressed into the wadding sheet but had only a smooth contact with the latter, it would slip under the light back drag of the roll brake. To prevent this back slip of the bottom cover sheet and insure its advance into the die zone along with the wadding sheet, and at the

same time maintain a sufficient reduced tension on the cover sheet to prevent the formation of wrinkles therein has been one of the objects of the present invention, and this we have accomplished on the principle of creating a slack in the cover sheet between successive feed movements, and applying just enough tension on the slack portion during the feed movements to insure smoothness and prevent wrinkling, without causing any back slip of the cover sheet on the wadding sheet.

An illustrative embodiment of the invention is shown in the accompanying drawings, in which—

Fig. 1 is a side elevation, partly in vertical section, showing our improvement and the parts of a sanitary napkin machine with which the improvement cooperates; the feed mechanism appearing at the end of its forward stroke and the cutting and embossing dies being open.

Fig. 2 is a similar view, but showing the feed mechanism at the end of its rearward stroke and the dies closed.

Fig. 3 is a plan section, viewed on the horizontal plane of the offset line 3—3 of Fig. 2.

Fig. 4 is a plan section through the die mechanism, showing a portion of the wadding sheet and top and bottom cover sheets lying on the lower die member.

Referring to the drawings, and first briefly describing those parts of the machine with which our improvement cooperates, 10 designates a flat table or platform mounted on side frames 11 and 12 and supporting a pair of uprights 13 in and between which is journaled a spool 14 carrying the roll 15 of creped paper wadding. In advance of the table 10 and in line therewith is the wadding feed mechanism comprising upper and lower clamps 16 and 17, the latter of which is reciprocated to and from the former to alternately grip and release the wadding as the latter is fed forward by a step-by-step movement into the zone of the cutting and embossing dies. The lower die 18 is stationary, and the upper die 19 reciprocates vertically and carries on its lower side a pair of embossing dies 20 for impressing on the ends of each napkin a trade name, as shown in Fig. 4. Associated with the upper die is a reciprocating plate 21 carrying on its under side a pair of V-shaped knives 22 that, as the die descends, make correspondingly shaped cuts 23 in the edges of the wadding to give the napkins the rounded end formation shown in Fig. 4. The clamp or gripper of the feed mechanism is reciprocated by a lever 24 that is pivoted between

its ends at 28 on a pair of brackets 26 supported on a cross bar 27 extending between the two side frames 11 and 12. The upper end of the lever 24 is connected by an adjustable link 28 to the lower side of the wadding clamp, and its lower end is connected by an adjustable link 29 to a slide 31 carrying a pair of rollers 32 between which operates a rotating cam 33.

Describing now our present improvement, 10 journalized in and between a pair of uprights 34 mounted on the platform 10 is a spool 35 carrying a roll 36 of smooth paper that forms the top cover sheet or strip. A lightly weighted apron 37 suspended from an overhead arm 38 lies in 15 contact with the surface of the roll 36 and functions as a brake to maintain the cover sheet under a light tension. Brackets 39 supported on the side frames 11 and 12 carry bearings for the spool 41 of a similar roll 42 of smooth paper 20 that constitutes the lower cover sheet for the wadding. The same brackets 39 may also carry lower bearings for the lower spool 43 of a spare supply roll 44.

The free end of the upper cover sheet from 25 the roll 36 is led under a rounded end 18' of the upper clamp member 16 onto the wadding sheet; and the lower cover sheet from the roll 42 is led over a guide roll 45 into contact with the under side of the wadding sheet. A weighted apron 46, 30 functionally similar to the apron 37, cooperates as a brake with the surface of the roll 42 to create a light tension on the lower cover sheet as it is drawn off. Pivotally mounted in and between a pair of lugs 47 on the under side of the 35 table 10 is a shaft 48, from which are suspended a pair of arms 49 in and between the lower ends of which is mounted a rod 51 that lies across that portion of the lower cover sheet between the roll 42 and the guide roll 45. This rod 51 is 40 drawn against the sheet so as to create a slack therein by a pull spring 52 that is connected at one end to one end of the rod 51, as shown in Fig. 3, and at its other end is anchored through a cord 53 to one of the transverse tie rods 54 45 connecting the side frames 11 and 12.

Clamped on the lever 24 is a horizontal arm 55 (Fig. 3), to the free end of which is connected a cord 56 that extends rearwardly around a guide pulley 57 attached to an oblique brace 58 50 of the frame, the portion of the cord beyond the pulley 57 being attached to the rod 51, substantially opposite the spring 52, as shown in Fig. 3.

Describing the operation, and assuming that the free ends of the two cover sheets have been 55 passed into contact with the wadding sheet within the clamp or gripper, when the lever 24 is swinging back from its forward or working stroke, it creates a slack in the cord 56 which allows the spring 52 to draw the rod 51 forwardly about 60 three inches, thus creating a slack in the portion of the lower cover sheet between roll 42 and guide roll 45, as clearly shown in Fig. 2; this three inch slack corresponding to the width of each napkin made by the cutting and embossing dies. When the lever 24 starts forward on its 65 working stroke, it creates a pull on the cord 56 which in turn draws the rod 51 rearwardly. This does not entirely eliminate the tension on the slack portion of the cover sheet, but reduces the 70 tension of the spring 52 to such an extent that it prevents any slip between the lower cover sheet and the wadding as the feed movement advances. The position of the parts at the conclusion of the forward feed movement is illustrated in Fig. 1.

The die operates to sever the foremost napkin by the knives 58 and 61 and simultaneously effect the end cuts 23 and emboss the second from the foremost napkin with the trade name, as shown at 62 in Fig. 4, during the return 5 stroke of the feed mechanism, the die members, of course, opening just prior to the next feeding stroke.

In Fig. 4 the wadding sheet forming the body of the napkin is indicated at A, the top covering 10 sheet at B, and the bottom covering sheet at C. It will readily be seen that the embossing dies 20 have the effect of locking together the portions of the top covering sheet B and the wadding sheet A, throughout the area of the embossments, and this renders it unnecessary to apply to the upper sheet a tension relieving mechanism such as above described in connection with the lower cover sheet. Since there is no such embossment on the under side of the napkin, the wadding and the lower cover sheet have only a friction contact, which would cause a back slip of the cover sheet on the wadding in the absence of any means for substantially reducing the normal tension on the cover sheet during the forward stroke of the feed mechanism. The mechanism shown and described for this purpose maintains just sufficient tension to keep the sheet smooth and avoid the creation of wrinkles.

Without limiting ourselves to the specific structural details herein shown and described,

We claim:

1. In a machine for making sanitary napkins, the combination with means for effecting a step-by-step feed of a sheet of absorbent wadding and a cover sheet for a side thereof through cutting dies, of means controlled by said feeding means for reducing the tension on said cover sheet during the feed movement sufficiently to prevent slip of said cover sheet on said wadding sheet.

2. In a machine for making sanitary napkins, the combination with means for effecting a step-by-step feed of a sheet of absorbent wadding and a cover sheet for a side thereof through cutting dies, of tension means for creating a slack in said cover sheet between successive feed movements, and means for reducing the pull of said tension means during each feed movement to a point where it is insufficient to cause a slip of said cover sheet on said wadding sheet.

3. In a machine for making sanitary napkins, the combination with means for effecting a step-by-step feed of a sheet of absorbent wadding and a cover sheet for a side thereof through cutting dies, of tension means for creating a slack in said cover sheet between successive feed movements, and means controlled by said feeding means for reducing the force of said tension means during each feed movement to a point where it is insufficient to cause a slip of said cover sheet on said wadding sheet.

4. In a machine for making sanitary napkins, the combination with means for effecting a step-by-step feed of a sheet of absorbent wadding and a cover sheet for a side thereof through cutting dies, of a supply spool for said cover sheet, a guide roll for directing said cover sheet from said spool to said feeding means, a bodily movable rod extending across said cover sheet between said spool and guide roll, a spring acting through said rod to create a slack in said cover sheet between successive feed movements, and means controlled by said feeding means for reducing the force exerted by said spring during each feed movement to a point where it is insufficient to

cause a slip of said cover sheet on said wadding sheet.

5. In a machine for making sanitary napkins, the combination with means, including a reciprocating lever, for effecting a step-by-step feed of a sheet of absorbent wadding and a cover sheet for a side thereof through cutting dies, of a supply spool for said cover sheet, a guide roll for directing said cover sheet from said spool to said feeding means, a pivotally suspended rod extending across said cover sheet between said spool and guide roll, a pull spring acting through said rod to create a slack in said cover sheet between successive feed movements, and means controlled 10 by said lever for lessening the pull of said spring during each feed movement to a point where it is insufficient to cause a slip of said cover sheet on said wadding sheet.
6. In a machine for making sanitary napkins,
- the combination with means, including a reciprocating lever, for effecting a step-by-step feed of a sheet of absorbent wadding and a cover sheet for a side thereof through cutting dies, of a supply spool for said cover sheet, a guide roll for directing said cover sheet from said spool to said feeding means, a pivotally suspended rod extending across said cover sheet between said spool and guide roll, a pull spring acting through said rod to create a slack in said cover sheet between successive feed movements, a cord connecting said lever with said rod, and cord-guiding means through which a movement of said lever in its feed direction causes said rod to swing in the opposite direction against the pull of said spring 15 and lessens the tension exerted by said rod on the cover sheet.
